DANIEL PIJZEL, OF BALIK PAPAN, BORNEO, DUTCH EAST INDIA.

APPARATUS FOR SWEATING CRUDE PARAFFIN-WAX OR LIKE MIXTURES OF SUBSTANCES WHICH MELT AT DIFFERENT TEMPERATURES.

1,070,730.

Specification of Letters Patent. Patented Aug. 19, 1913.

Application filed June 27, 1911. Serial No. 635,632.

To all whom it may concern:

Be it known that I, DANIEL PIJZEL, chemical engineer, residing at Balik Papan, Borneo, in Dutch East India, Kingdom of the Netherlands, have invented certain new and useful Improvements in Apparatus for Sweating Crude Paraffin-Wax or Like Mixtures of Substances which Melt at Different Temperatures, of which the following is a specification.

The object of my present invention is an apparatus for sweating crude paraffin-wax or like mixtures of substances which melt at different temperatures.

15 An apparatus serving for carrying out this continuous sweating process is shown in the accompanying drawings in which:—

Figure 1 is a longitudinal section of the sweating stove. Fig. 2 is a transverse section through the delivery end of the oven, looking toward the left in Fig. 1, and showing the air heating chamber arranged over the tunnel; Fig. 3 is a transverse section on a larger scale, showing details of construction; Fig. 4 is a detail and longitudinal elevation and on a plane at right-angles to that of Fig. 3; Fig. 5 is a plan of the delivery end of the oven; and Fig. 6 is a similar plan of the entrance end of the oven.

30 The oven consists of a long passage *a* provided with rails on which the sweating vessels placed on trucks or cars *b* are run into the oven. The passage is closed at both ends by an air lock *c* and *d* respectively, each of which is large enough to take one sweating truck. The bottom of the passage is made sloping, whereby the moving forward of the trucks is facilitated and the sweating trucks have such a position that the product 35 sweated out can immediately run off. Over the oven there is an air passage *g* which connects with an air heating device arranged at the lowest end of the oven. This heating device consists of a chamber *z* in which are arranged corrugated pipes *f* heated by exhaust steam. In the chamber there is also a fan *e* which draws the air out of the air passage *g* and forces it toward the heating device, whence it flows heated into the 40 sweating oven *a*, in order to again enter the air passage *g*. The air passage is connected

at suitable places with the oven *a* by apertures which may be closed by dampers or slides *h*¹, *h*², *h*³. If the dampers *h*¹, *h*², *h*³ are opened, a portion of the oven air flows 55 through the damper apertures to the fan, whereby the quantity of air flowing through the upper cold end of the passage is diminished. In this way a slower heating may be obtained at the commencement of the sweating process.

The air lock *d* provided at the lower warm end of the passage *a* is provided with steam heating pipes *i* and a direct boiler steam pipe, in order to enable the final product 65 of the sweating process to be fully melted out therein. At the side of the passage there is provided near the rails a gutter *k*, (Fig. 5), which is divided by partitions *k*¹ into compartments equal to the length of a 70 sweating truck. Each of these compartments has a discharge pipe *l* to the outside, so that the sweating products running off the truck may be carried off from each truck separately. If necessary two or more drain 75 gutters *k* may also be provided.

The construction of the truck may be seen in Figs. 2, 3 and 4. The sweating frames placed thereon are of very simple nature, as all cocks, valves and pipes for supplying and carrying off of steam, water and paraffin-wax are dispensed with. The car or truck consists of an under frame *n* with a number of, for instance six, columns or uprights, half of which *t* are arranged on one 80 side and the other half *u* on the other side of the car (see Fig. 3). On the uprights *t*, eight pieces of U-iron *s* are riveted one above the other for receiving the sweating trays, while the uprights *u* carry corresponding 85 angle irons *r* which are arranged somewhat lower in order to give the sweating trays an inclined position. A discharge pipe *w* with a revoluble outlet nozzle *m* is fixed on one upright *u* of the car or truck, by means of 90 which nozzle the molten products flowing from the pipe *w* are suitably distributed into the gutters *k*, whereby it is possible to sweat out in the same oven simultaneously 95 different kinds of material and to collect 100 them separately.

The trays have a bottom *o* made of corrugated iron.

gated galvanized iron, to which a wire gauze bottom p is attached. The trays have only three sides consisting of angle iron, which are riveted or screwed to the corrugated plate and hold the gauze on three sides, while the fourth side of the gauze bottom is directly connected by rivets or screw bolts and nuts with the corrugated plate. This side of the tray is pushed into the U-irons s of the truck and forms in this way the uppermost part of the inclined tray, see Fig. 3; on the opposite side of the tray a drain gutter v is arranged, the lateral outlet pipe x of which is brought over a catch cup y of the pipe w .

The way in which the improved process is carried out and the crude paraffin-wax introduced into the trays is as follows: The crude paraffin-wax is poured into ordinary cooling trays or cooling ponds and when it has set is cut into blocks (cakes). These paraffin-wax blocks are then placed on the gauze bottom of the trays and pushed into the truck frame. When the truck is filled with the material, it is run into the air lock c and from this into the oven passage a . Here the truck enters the coldest end of the oven and gradually travels to the lower and warmest end of the oven, while the hot air flows against the truck in the opposite direction. In this way a partial melting out of the paraffin-wax takes place, and at the uppermost and less heated part of the oven the oils and paraffin-wax of low melting point and at the lowest and warmest part of the oven the paraffin-wax of higher melting point is sweated out. The trucks must be run into the inclined passage in such a way that they stand at an inclination to the end where the collecting pipe is located. Consequently the drain gutters v which serve for receiving the products dropping through the gauze bottom onto the inclined corrugated plate and running off the latter have the same inclination, so that these products pass immediately through the outlet pipe x into the catch cups y of the collecting pipe w . Now as the outlet nozzle m arranged at the lower part of the pipe w is adjusted over one of the gutters h , the molten substances flow directly out of the pipe w into one of these gutters h , whence they are carried off through a pipe l .

When a truck has passed through the oven passage it comes into the air lock d where the final product of the paraffin-wax is melted out by means of fresh steam. The outer door of the air lock d is then opened, the truck run out and the door again closed. A sliding door located between the air lock d and the oven a is then opened by being drawn up and the truck which stands next to the air lock d runs into the latter, whereupon all the trucks contained in the oven

passage a can advance one truck length. The sliding door between the air lock c and the oven a is opened by lifting and the truck contained in the air lock c run into the oven. When the sliding door is again closed the outer door of the air lock c is opened and a fresh truck run into it.

The air locks c and d are only in communication with the external air for a short time during the opening of the outer doors, while the trucks are run in and out. The loss of heat by radiation is therefore very small. The actual sweating stove a on the other hand is never in communication with the outer air as one of the two doors of each air lock is always closed. The fan e draws the air from the air-duct g and forces it through the heating body f into the oven-passage a . Here the hot air flows past the trucks b and causes the paraffin-wax cakes located thereon to sweat out. When the air has passed through the passage a it rises into the air passage g in order to be afresh drawn up by the fan. The air is thus in continuous circulation.

In the accompanying drawings an apparatus is shown, the oven of which is designed to receive sixteen trucks. Each truck is loaded with 3.2 to 3.5 tons of crude paraffin-wax. The apparatus can therefore, when the trucks pass through the oven once every 24 hours, treat 50 tons of crude paraffin-wax per day. Every $1\frac{1}{2}$ hours a sweated out truck must therefore be run out and a fresh charged truck run in. By diminishing the number of the trucks or by employing smaller trucks the oven may also be arranged for a smaller production. In consequence of the great speed at which the hot air is blown through the tunnel, the temperature is prevented from differing in the upper and lower parts of the same section of the tunnel, whereby the sharpness of the fractional separation is insured.

By varying the temperature and the speed of the air the increase of temperature may be so selected from one truck to another, that the sweating process takes place under as favorable conditions as possible. Only because in this process all the trucks may be filled at a suitable place outside the oven with the paraffin which is to be sweated out, it is possible without complicated conveying mechanisms to allow it to set in separate cooling trays or on a cooling basin instead of filling it in a molten condition directly to the sweating trays, and the solidified paraffin-wax to be loaded in a solid form on the sweating trucks, thus rendering it unnecessary to construct the sweating trays in such a way that they have to be filled with water and molten paraffin-wax. Further the casting of the crude paraffin-wax into simple cooling trays or into masonry

cooling ponds filled with water is in every respect more convenient and cheaper than pouring it directly into the melting trays, especially as an efficient system of water cooling can be much more easily arranged in the first case.

This improved process has all the advantages of a continuous circulatory process, without having the disadvantage of intermittent operation, as will be explained in the following: The principal advantage of the improved process consists in its greater capacity of production. This is based on the circumstance, that the entire plant with the exception of at the most two trucks, which are in the air locks, or being loaded is constantly subjected to the sweating process. The sweating surface in this process therefore only requires to be about one half or one third as large as in the intermittently working plant in order to give the same yield. Further in consequence of the use of the counter current principle in this improved process, the heat is very favorably utilized and any loss of heat is restricted to the smallest amount by the use of the air locks. The rapid flow of air caused by the fan through the sweating tunnel also diminishes the differences of temperature between the upper and lower parts of the sweating frame, so that the sweating out takes place with uniform rapidity in all the trays. The speed of the sweating out may also be adjusted with certainty by adjusting the fan and the air dampers h^1 , h^2 , h^3 . Finally as the sweated products are always run off immediately, the fractional separation is substantially sharpened. The construction of the trays and trucks also offers many advantages. The corrugated plate gives the gauze a good and cheap support, so that depressions in the same and accumulations of oil produced thereby are avoided. The gauze bottoms may also be repaired and cleaned without much trouble and loss of time. These advantages are afforded even if the trucks be employed in the old intermittently working ovens, but the combined use of the constantly acting tunnel and the improved trucks is preferable, even for small installations, as only in this way can all defects of the present system be removed.

Claims.

1. An oven for sweating paraffin, comprising a long tunnel-like chamber, a track on the bottom thereof, a heating device at the rear end of said chamber, a flue leading from the heating device to the open rear end of said chamber, a return flue connected to the front end of the chamber and leading back to said heating device, and means for forcing air over said heating device.

2. An oven for sweating paraffin, comprising a long tunnel-like chamber, a track on

the bottom thereof, a heating device at the rear end of said chamber, a flue leading from the heating device to the open rear end of said chamber, a return flue connected to the front end of the chamber and leading back to said heating device, and means for forcing air over said heating device, the roof of said chamber having valved apertures connecting the chamber and return flue.

3. An oven for sweating paraffin, comprising a long tunnel-like chamber, a track on the bottom thereof, a heating device at the rear end of said chamber, a flue leading from the heating device to the open rear end of said chamber, a return flue connected to the front end of the chamber and leading back to said heating device, means for forcing air over said heating device, an entrance chamber at the front end of the tunnel chamber having a door at each end, and a like exit chamber at the rear end, said exit chamber having a heating device therein.

4. An oven for sweating paraffin comprising a long tunnel-like chamber, a track for tray-carriers on the bottom thereof, gutters alongside of said tracks, each of the same length as said tray-carriers, and delivery pipes, leading to the outside of the oven.

5. An apparatus for sweating paraffin and the like, comprising a normally closed sweating chamber, a duct above the top of said chamber, openings at each end of the duct establishing communication between said chamber and duct, independently closable openings in the top of said chamber intermediate the end openings and communicating with said duct, a heating chamber at one end of said duct, heating means therein, and means to produce a continuous circulation of air through said sweating chamber, duct and heating chamber.

6. An apparatus for sweating paraffin and the like, comprising a normally closed sweating chamber, an entrance air lock at one end of said chamber, an exit air lock at the other end of said chamber, means to advance a paraffin carrier through said entrance air lock, sweating chamber, and exit air lock, means to gradually raise the temperature of the paraffin carrier as it passes through the sweating chamber, means to separately remove the products sweated out at different temperatures in the sweating chamber, means to heat the carrier in the exit air lock, and means to remove the carrier from the exit air lock.

7. An apparatus for sweating paraffin and the like comprising a sweating chamber, an entrance air lock, an exit air lock, means to admit a paraffin carrier to said chamber through said air lock, means to advance said carrier through said chamber, means to cause a circulation of air through said chamber in a direction opposite to that in which

the carrier is advanced, means to heat said circulating air, means to maintain a higher temperature at the exit air lock end than at the entrance air lock end of the sweating chamber, and means to separately collect and remove products sweated out at different points in said sweating chamber.

In testimony whereof I affix my signature in presence of two witnesses.

DANIEL PIJZEL.
